UNITED STATES PATENT OFFICE.

EDWARD J. BROOKS, OF EAST ORANGE, NEW JERSEY.

SEAL-PRESS.

SPECIFICATION forming part of Letters Patent No. 595,282, dated December 7, 1897.

Application filed September 2, 1897. Serial No. 650,392. (No model.)

To all whom it may concern:

Be it known that I, EDWARD J. BROOKS, a citizen of the United States of America, and a resident of East Orange, in the State of New Jersey, have invented a new and useful Improvement in Seal-Presses, of which the following is a specification.

This invention is additional to my improvements in seal-presses patented May 6, 1884, by Letters Patent No. 298,284; September 22, 1885, No. 326,897; October 13, 1885, No. 328,106; October 14, 1890, No. 438,140; November 1, 1892, No. 485,370, and October 20, 1896, No. 569,742.

15 The object of the present invention, in common with said patented improvements, is to insure securely fastening each seal at the pressing operation and providing the same in the press with sharp and distinct lettering or 20 other distinguishing marks, if need be, to which end each press is provided with a "ratchet attachment" to prevent reopening the lever-handles after the pressing operation is begun until the dies have been closed to a 25 predetermined extent necessary to perfectly compress the seal-disk or its equivalent.

In common with the improvement set forth and claimed in said Patent No. 569,742 another object of the present invention is to 30 adapt a "hammer" seal-press to so operate.

The present invention consists in certain novel combinations of peculiarly constructed and arranged parts, whereby the construction of the ratchet attachment is further simplified, while the adaptation of the head of the press to serve as a hammer for labeling railway freight-cars or pieces of freight or baggage is maintained in a peculiar manner and the manipulation of the press as a whole 40 is facilitated.

Two sheets of drawings accompany this specification as part thereof.

Figure 1 of the drawings is a side view of an improved seal-press, partly in section, 45 showing the lever-handles in two positions by full and dotted lines. Fig. 2 represents a longitudinal section in a central plane parallel to that of Fig. 1. Fig. 3 represents side and edge views of the ratchet attachment 50 proper, detached. Fig. 4 represents side and edge views of the head of the press segregated. Fig. 5 is a small-scale side elevation

showing the lever-handles at the extremes of their movements by full and dotted lines. Fig. 6 is a perspective view of the press-fas- 55 tened seal produced by the dies shown in the previous figures. Fig. 7 is a side view of the head end of a modified form of said improved press. Fig. 8 represents a central longitudinal section through the same. Fig. 60 9 is a side view of its head segregated. Fig. 10 is a small scale side view of the press complete, showing its lever-handles at the extremes of their movements; and Fig. 11 is a 65 face view of a seal fastened and stamped by means of the press represented by said Figs. 7 to 10, inclusive.

Like letters and numbers refer to like parts in all the figures.

In either form said improved seal-press com- 70 prises a recessed head H, having a pair of cheeks 1 and 2, which support a pair of fulcrum-pins a and b. The front of the head H is conveniently open from top to bottom, its mouth m being formed in the front edges of 75 said cheeks by reentrant curves, and a "bed-die" d is located inside of said mouth within the head. A pair of lever-handles A and B, fulcrumed on said pins a and b, carry, re- 80 spectively, a movable die d² and a die-clos- 85 ing cam c, and said lever-handle A is pro- 90 vided with a stop x to limit the die-closing movement. Said cheek 1 is provided with an arc-shaped ratchet-rack r, concentric with 95 said fulcrum-pin b and constructed with re- 100 versing-notches 3 and 4 at its respective ends, and the corresponding side of the lever-han- 100 dle B is provided with a ratchet attachment r², Fig. 3, consisting of a pawl 5, to coact with said rack, a spring 6, and a follower 7, tend- 90 ing to hold said pawl in effective position, and a housing 8, recessed to accommodate 95 said pawl, spring, and follower, and attached by screws 9 and 10, said screw 9 forming a pivot parallel with said fulcrum-pins a and b, 95 upon which the pawl 5 reverses when its point enters either of said notches 3 and 4 preparatory to the next stroke of said lever-handle B. At the notch 3 the pawl engages the rack r for the effective stroke of the lever-handle 100 and remains interlocked with its teeth until the pressing operation is fully completed, as illustrated by Fig. 1. When the pawl 5 en- 100 ters the notch 4 at the instant when the press

is fully closed, as represented by the dotted-line position in Figs. 1, 5, and 10, the pawl reverses on its pivot, so as to ride back over the teeth of the rack *r* to the notch *3*. A flange *f* on the housing *8* overlaps the cheek *1* sufficiently to mask the pawl *5* and prevent tampering therewith.

Countersinks *z* and *y* in the cheeks *1* and *2* accommodate, respectively, screw-heads on the fulcrum-pins *a* and *b* and screw-nuts which secure the same in the construction represented by the drawings.

Die-opening springs *s* and *s*², Fig. 2, or *s'*, Fig. 8, are supported in spring-seats *11* within the heads *H* and coact with the die ends of the lever-handles *A* and act therethrough on the cams *c* of the lever-handles *B*, and said spring-seats are conveniently located in line with hammer-face projections *h*, so that the springs are perpendicular to the hammer-faces, as shown in said Figs. 2 and 8. When either press is fully closed, as in dotted lines in Figs. 1, 5, and 10, said springs, die end, and cam form an effective backing behind the hammer-face and render the seal-press adapted in a superior degree for use as a hammer in labeling cans and like work usually entrusted to the sealer, so as to obviate carrying an additional tool for the purpose.

The dies *d* and *d*² of the specific press represented by Figs. 1 to 5, inclusive, are adapted to fasten my tin shackle-seal, patented August 21, 1894, by Letters Patent No. 524,975, as made without a rivet under claim 1 of said patent. The bed-die *d* is accordingly constructed with a central gage-pin *13* to occupy the eyelet-hole *14*, Fig. 6, of that seal and the movable die *d* with an axial hole *15* to admit said pin when the dies are closed, and the faces of both dies may be smooth and flat surfaces, the seal's distinguishing marks *16*, Fig. 6, being printed on the shackle at the factory. In said seal-press, Figs. 1 to 5, inclusive, both dies are conveniently fastened in place by laterally-projecting screws *e*, and the ratchet-rack *r* is integral with the cheek *1* of the head *H*, being conveniently cut into its edge.

In the modified press represented by Figs. 7 to 10, inclusive, the ratchet-rack *r* is detachable, as shown in Fig. 9, so as to be renewed, if broken, without discarding the head *H* as a whole. The dies *d* and *d*² are adapted to lead and wire seals, and the bed-die *d* is held in place by an axial screw *e'*, Fig. 8.

The specific pressed seal represented by Fig. 11 is one of my seals, patented August 4, 1885, by Patent No. 323,849, as indicated by its zigzag wire *17*, and is not only securely fastened in the press, but at the same time provided with sharp and distinct distinguishing marks *18*, including appropriate lettering.

The die-opening springs shown at *s* and *s*², Fig. 2, are spiral springs of suitable wire, one within another, while *s'*, Fig. 8, represents a flat metal volute spring. One or more springs

of other forms may be substituted. The dies may be adapted to any style of press-fastened seals, whether their distinguishing marks are put on at the factory or stamped on at the pressing operation. The dies may be integral with the head-casting and with the die-carrying lever-handle, respectively. Ordinary or improved fulcrum-pins may take the place of the screw-pins shown in the drawings, rivets may take the place of the screws 75 9 and 10, and other like modifications will suggest themselves to those skilled in the art.

Having thus described said improvement, I claim as my invention and desire to patent under this specification—

1. A seal-press comprising a die-inclosing head having a pair of cheeks which support a pair of fulcrum-pins, one of said cheeks carrying an arc-shaped ratchet-rack concentric with one of said pins, a pair of lever-handles fulcrumed on said pins and provided respectively with the movable die and with a die-closing cam, and a pawl, carried by the lever-handle last named, reversing on a pivot parallel to said fulcrum-pins, and coacting with said ratchet-rack, to insure fully closing the dies at each pressing operation.

2. The combination, in a seal-press, of a die-inclosing head having a pair of cheeks, one of which carries on its edge an arc-shaped ratchet-rack having reversing-notches at its ends, a pair of lever-handles one of which carries a die-closing cam and is fulcrumed on a pin concentric with said rack, a rack-engaging pawl carried by the lever-handle last named and reversing on a pivot parallel to said fulcrum-pin, and a pawl-inclosing housing having a flange at its outer side which overlaps said rack-carrying cheek, substantially as hereinbefore specified.

3. The combination, in a seal-press, of a recessed head provided internally with a bed-die, a pair of lever-handles fulcrumed separately within said head and provided respectively with the movable die and with a die-closing cam, and a die-opening spring or springs, within said head, acting on the die-carrying end of the lever-handle first named, substantially as hereinbefore specified.

4. The combination, in a seal-press, of a recessed head containing a bed-die and provided with a hammer-face and a spring-seat behind the same and perpendicular thereto, and a pair of lever-handles fulcrumed within said head and provided respectively with the movable die and with a die-closing cam, and a spring or springs within said spring-seat, acting on the die-carrying end of the lever-handle first named, substantially as hereinbefore specified.

EDWARD J. BROOKS.
